UNITED STATES PATENT OFFICE.

MATTHEW R. HULL, OF CONNERSVILLE, INDIANA, ASSIGNOR TO REX MANUFACTURING COMPANY, OF CONNERSVILLE, INDIANA, A CORPORATION OF INDIANA.

CONNECTING MEANS FOR TWO-PART AUTOMOBILE DOORS.

Application filed March 29, 1924. Serial No. 702,958.

To all whom it may concern:

Be it known that I, MATTHEW R. HULL, a citizen of the United States, residing at Connersville, in the county of Fayette and

5 State of Indiana, have invented certain new and useful Improvements in Connecting Means for Two-Part Automobile Doors, of which the following is a specification.

My said invention relates to a connector 10 for two-part doors such as are used on automobiles having demountable winter tops, the upper door section being attached to the permanent lower section in a manner to be readily demountable. It is an object of 15 my invention to provide a connector of simple and inexpensive form which is so constructed as to bias the upper and closing sides of the upper door section toward the vehicle body and secure a close but yielding joint when the door is closed.

Referring to the drawings which are made a part hereof and on which similar reference characters indicate similar parts;

Figure 1 is a side elevation of an automobile door embodying my invention, the view showing the inner side of the door;

Figure 2 a fragmentary elevation showing the connector at the hinge side of the door as viewed from the left; and

30 Figure 3 a similar view of the connector at the closing side of the door viewed from the left.

In the drawings reference character 10 indicates a demountable door section and 11 35 a permanent door section. The demountable section includes a wooden frame having upper and lower members 11 and 12 and side members 13 and 14 which support the parts of the door and one or more panes 40 of glass, 15.

A connector is mounted at the hinge side 45 of the door this connector having upper and lower arms 16 and 17 respectively connected by a normally horizontal body 18. The arm 17 projects into a socket in the permanent door section and the arm 16 into a socket on the demountable door section this socket being here shown as provided by securing a strip of sheet metal 19 to the 50 frame member 13 with its opposite sides extending over opposite sides of the frame member secured thereto by means of nails and the like. A bracket 20 is fixed to the bar 12 as by means of a screw 21 and a rivet 22, 55 said bar having an opening receiving the

body of the connector which opening may be cylindrical or may consist merely of a pair of ridges lying closely adjacent to said body.

A similar connector is secured in similar 60 manner to the closing side of the door, this connector having arms 23 and 24 which may be similar in every respect to the arms 16 and 17 except that they lie in diverging planes intersecting at the body as clearly 65 shown in Figure 3. The effect of this is that in order to maintain the upper section on the lower section the arm 24 must be forced toward a plane common to all parts of the connector thereby twisting the body portion. 70 When the arm is now forced into the socket in the lower door section the torsional strain of the connector tends to tilt the upper door section in a manner to bias its upper and closing sides toward the vehicle body. 75

It will be obvious to those skilled in the art that changes may be made in my device without departing from the spirit of the invention, and therefore I do not limit myself to the precise construction shown in the 80 drawings and described in the specification but only as indicated in the appended claims, for example, a connector might be placed at the hinge side similar to that at the closing side or the connectors might be 85 interchanged or one of the connectors might be replaced by different means having the same function and the lower arms might be connected to the lower door section in various other ways. 90

Having fully described my said invention what I claim is:

1. In a two-part door for vehicles, a demountable upper door section, a permanent lower door section, a connector at the hinge 95 side of the door comprising upper and lower parallel arms secured to the respective sections and an angularly related body in the same plane with the arms said body being fixed to the upper section, and a similar connector similarly secured at the closing side of the door the last-named connector having its arms located in diverging planes whereby when it is forced into position on the lower door section the body of the connector 100 is twisted to bias the upper edge, of the demountable door section toward the vehicle body, substantially as set forth.

2. In a two-part door for vehicles, a demountable upper door section, a permanent 110

- lower door section, a pair of sockets on the upper section near opposite sides thereof, a pair of sockets on the lower door section spaced inwardly from those first named all 5 of the sockets being normally parallel, and a pair of connectors each having a horizontal body secured along the lower side of the upper door section, an ascending arm in an upper socket, and a depending arm in 10 a lower socket the arms on one connector being located in diverging planes to bias the upper edge of the demountable section toward the door frame, substantially as set forth.
- 15 3. In a two-part door for vehicles, a demountable upper door section, a permanent lower door section, a pair of sockets on the upper section near opposite sides thereof, a pair of sockets on the lower door section

spaced inwardly from those first named all 20 of the sockets being normally parallel, and a pair of connectors each having a horizontal body secured along the lower side of the upper door section, an ascending arm in an upper socket, and a depending arm in 25 a lower socket the arms on the connector at the closing side being located in diverging planes to bias the closing side of the demountable section toward the door frame, substantially as set forth.

30 In witness whereof, I have hereunto set my hand and seal at Connersville, Indiana this 25th day of March, A. D. nineteen hundred and twenty-four.

MATTHEW R. HULL. [L. S.]
